US0D1049481S

(12) **United States Design Patent** (10) **Patent No.:** **US D1,049,481 S**
(45) **Date of Patent:** **** Oct. 29, 2024**

(54) **PORTABLE VAPORIZATION ASSEMBLY**

(71) Applicant: **Puff Corporation**, Los Angeles, CA (US)

(72) Inventors: **Avinash Bajpai**, Aguora Hills, CA (US); **Tanner Wills**, Los Angeles, CA (US); **Siddhant Waghmare**, Los Angeles, CA (US); **Roger Volodarsky**, Glendale, CA (US)

(73) Assignee: **Puff Corporation**, Los Angeles, CA (US)

(**) Term: **15 Years**

(21) Appl. No.: **29/926,107**

(22) Filed: **Jan. 29, 2024**

(57) **CLAIM**

The ornamental design for a portable vaporization assembly, as shown and described.

DESCRIPTION

FIG. 1 is a front perspective view of an embodiment of the portable vaporization assembly;

FIG. 2 is a front view thereof;

FIG. 3 is a rear view thereof;

FIG. 4 is a side view thereof;

FIG. 5 is an opposite side view thereof;

FIG. 6 is a top view thereof;

FIG. 7 is a bottom view thereof;

FIG. 8 is a front perspective view of another embodiment of the portable vaporization assembly;

FIG. 9 is a front view thereof;

FIG. 10 is a rear view thereof;

FIG. 11 is a side view thereof;

FIG. 12 is an opposite side view thereof;

FIG. 13 is a top view thereof; and,

FIG. 14 is a bottom view thereof.

The broken lines depict portions of the portable vaporization assembly that form no part of the claimed design.

1 Claim, 14 Drawing Sheets

Related U.S. Application Data

29/835,960, filed on Apr. 22, 2022, now Pat. No. Des. 1,008,541, which is a continuation of application No. 17/407,446, filed on Aug. 20, 2021, now Pat. No. 11,375,752.
